[57] CLAIM

The ornamental design for a sports bag for bat and balls, as shown.

DESCRIPTION

FIG. 1 is a perspective view of a sports bag for bat and balls, showing my new design;

FIG. 2 is a left side elevational view thereof;

FIG. 3 is a front elevational view thereof;

FIG. 4 is a rear elevational view thereof;

FIG. 5 is a bottom plan view thereof;

FIG. 6 is a front elevational view with strap clipped. The broken line showing of a person, bicycle, and bat in FIG. 1 and a bat in FIGS. 2, 3, 4, and 6 is for illustrative purposes only and forms no part of the claimed design.

FIG. 1

UNITED STATES PATENT AND TRADEMARK OFFICE
CERTIFICATE OF CORRECTION

PATENT NO. : Des. 316,631

Page 1 of 4

DATED : May 7, 1991

INVENTOR(S) : Anna J. Hammons

It is certified that error appears in the above-identified patent and that said Letters Patent is hereby corrected as shown below:

The title page should be deleted to appear as per attached page.

IN THE DRAWINGS:

The directional arrows 3-3, 4-4 and 5-5 should be deleted from Figs. 2 and 4, as shown on the attached pages.

Signed and Sealed this
Third Day of November, 1992

Attest:

DOUGLAS B. COMER

Attesting Officer

Acting Commissioner of Patents and Trademarks
